United States Patent Office

Des. 181,396
Patented Nov. 5, 1957

181,396

INFANT'S SHOE

Frank J. Winter, Jr., Ferguson, Mo.

Application March 21, 1957, Serial No. 45,394

Term of patent 14 years

(Cl. D7—7)

FIG1

I claim:

The ornamental design for an infant's shoe, as shown.
